(57) **CLAIM**

The ornamental design for a clear top scale, as shown and described.

DESCRIPTION

FIG. 1 is a top front perspective view of a clear top scale showing my new design in the closed position;

FIG. 2 is a top front perspective view of the scale shown without the clear top for clarity of illustration;

FIG. 3 is a left side perspective view of FIG. 2; and,

FIG. 4 is a top front perspective view of the clear top scale shown in the open position with the clear top placed on top of the scale as a tray.
